CLAIM

The ornamental design for an electrical power unit for a work surface, as shown and described.

DESCRIPTION

FIG. 1 is a front perspective view of a first embodiment of the electrical power unit for a work surface showing our new design;

FIG. 2 is a front elevation thereof;

FIG. 3 is a top plan view thereof;

FIG. 4 is a front perspective view of a second embodiment of the electrical power unit for a work surface showing our new design;

FIG. 5 is a front elevation thereof;

FIG. 6 is a top plan view thereof;

FIG. 7 is a front perspective view of a third embodiment of the electrical power unit for a work surface showing our new design;

FIG. 8 is a front elevation thereof;

FIG. 9 is a top plan view thereof;

FIG. 10 is a front perspective view of a fourth embodiment of the electrical power unit for a work surface showing our new design;

FIG. 11 is a front elevation thereof;

FIG. 12 is a top plan view thereof;

FIG. 13 is a front perspective view of a fifth embodiment of the electrical power unit for a work surface showing our new design;

FIG. 14 is a front elevation thereof; and,

FIG. 15 is a top plan view thereof.

In the drawings, the broken lines are for the purpose of illustrating environment only and form no part of the claimed design.

1 Claim, 8 Drawing Sheets
